VARIABLE FREQUENCY STROBOSCOPE

Benjamin Miller, Richmond Hill, N. Y., assignor
to Doherty Research Company, New York,
N. Y., a corporation of Delaware

Application June 15, 1934, Serial No. 730,741

19 Claims. (Cl. 176—124)

This invention relates generally to electric impulse producing apparatus. It is particularly concerned with an improved variable frequency stroboscope.

5 The present invention is a continuation in part of and improvement on that described in my copending application Serial No. 709,901, filed February 5, 1934. In my aforesaid copending application I have described a novel form of an 10 electric flash producing apparatus including as elements a gaseous conductor stroboscope lamp of the type in which discharge across two main electrodes is initiated by an appropriate stimulus applied to a third electrode; together with a condenser shunted across two main electrodes, and a 15 circuit for charging the condenser. The flash producing apparatus described in my aforesaid copending application was particularly developed for examining stroboscopically the timing of a variable speed spark ignition engine and for 20 accurately determining the speed of the engine; and for this purpose excitation of the lamp is effected by applying the ignition impulse of the engine to the third electrode of the lamp.

25 The term "trigger tube" will be herein employed to designate a gaseous conductor device in which conduction of current through a gaseous medium between two primary electrodes is initiated by applying the proper stimulus, as for 30 example by changing the potential of a third electrode. A further description will be found in my aforesaid copending application.

A particular object of the present invention is to provide an improved variable frequency stroboscope which is adapted for general use in 35 examining engines and other moving elements.

Impulses suitable for initiating discharge of a condenser through a gas or vapor tube stroboscope lamp may be obtained by interrupting the 40 current in the primary of a transformer such as an automotive ignition coil, by including in the primary circuit a rotary circuit breaker, a storage battery, and drive for the circuit breaker. The rate of flashing is then controlled by the speed of 45 the circuit breaker.

By having the element to be examined drive the circuit breaker, the flashes are synchronized with the element, so that the stroboscopic effect is produced. This method has the disadvantage 50 that an appreciable current must be interrupted by the rotary circuit breaker, so that a special construction of circuit breaker is required in order to maintain accurate timing of the flashes, and this special type of circuit breaker requires a 55 considerable amount of power to operate. The

method may be improved by substituting for the circuit breaker a contactor in the grid circuit of a trigger tube, whereby a condenser is suddenly charged or discharged through the trigger tube and primary of the transformer. This requires 5 less power, and is more generally applicable, but there remain cases in which the element to be examined cannot be made to provide the impulses, even by the photo electric cell method described in my copending application Serial No. 10 709,901. For such cases it is necessary to use an impulse generator whose rate can be controlled. One method is to use a circuit breaker or contactor driven by some means independent of the element to be examined, such as a motor; 15 means must then be provided for varying the speed.

The use of an auxiliary moving element and of a variable speed drive mechanism involves complications which I desire to avoid, so that a primary object of the present invention is to provide an improved combination of a condenser discharge stroboscope with an impulse generator embodying no moving elements and which requires only the variation of an impedance to 25 control the rate of flashing.

The impulse generator of the present invention consists essentially of a static inverter in which a condenser is suddenly charged or discharged through a gaseous conductor device at 30 intervals controlled by varying an impedance in the circuit, and the sudden current flow through the gaseous conductor device is used to generate the impulse which is conducted to the exciting electrode of a stroboscope lamp. The invention 35 comprehends two types of static inverter—the driven type and the self-excited type. I prefer to employ that variety of self-excited inverter known as a relaxation inverter when a wide range of flashing rates is to be covered, but I have provided a new type of self-excited inverter which is 40 particularly suited for very precise frequency control, as will be more fully discussed below.

The driven static inverter comprises a variable 45 frequency vacuum tube oscillator, a condenser, means for charging the condenser, and a trigger tube. The alternating current generated by the vacuum tube oscillator is impressed on the grid of the trigger tube, whereby current flows through the trigger tube, in pulses whose frequency is 50 equal to the frequency for which the oscillator is set, to charge or to discharge the condenser. Vacuum tube oscillators are so well known that it is not necessary to describe one; that type 55 known as a multivibrator is suitable. From the

- description of the use of the various modifications of self-excited static inverters, those skilled in the art will readily understand how to modify the circuits shown to use a driven inverter. Since 5 the self-excited inverter requires fewer parts and is simpler to build and operate, it is preferred, but the invention is limited only by the appended claims.
- Other objects of the invention are: to provide 10 a stroboscopic tachometer of the type described in my copending application Serial No. 709,901 embodying a ratiometer adapted to give impulse rate readings which are independent of voltage variations; to provide a static inverter which 15 employs a trigger tube, and which is adapted to furnish impulses at a controlled rate, which rate is relatively insensitive to supply voltage changes and substantially independent of variations in trigger tube characteristics; and to provide an 20 impulse generator which is adapted for exciting a stroboscope and which is a static inverter employing a trigger tube in a circuit which allows a wide range of impulse rates to be covered by means of a simple control.
- 25 With the above and other objects and features in view, the invention resides in the variable frequency stroboscope which is hereinafter described and particularly defined in the accompanying claims.
- 30 The present invention will be hereinafter more particularly described by reference to the accompanying drawings, in which:

Fig. 1 is a wiring diagram of a condenser discharge trigger tube stroboscope having an exciting electrode connected to the secondary of a transformer, in which flashes of the tube are initiated by impulses impressed on the primary of the transformer by means of a static inverter embodying a gaseous discharge device connected 35 in shunt circuit with a condenser; together with a source of potential, and a variable impedance for varying the impulse rate.

Fig. 2 is a wiring diagram of a modified arrangement of the apparatus shown in Fig. 1 40 in which the gaseous discharge element of the static inverter is connected in series circuit with the condenser and with a source of potential.

Fig. 3 is a wiring diagram of an improved form 45 of electrical impulse generator comprising a condenser, a charging circuit for the condenser which is a slightly damped oscillating circuit including an electric check valve, an inductance and a variable impedance, and a condenser discharge circuit comprising the primary of a transformer and a trigger tube.

Fig. 4 is a wiring diagram of a preferred form 50 of the invention in which a ratiometer is embodied as a rate meter, and in which the static inverter circuit embodies a pentode and glow tubes whereby to increase the flexibility and reliability of the impulse rate control.

Figs. 1 to 4 show trigger tube stroboscopes of 55 the condenser discharge type in which a trigger tube 10 of the neon lamp type has its cathode and anode respectively connected by leads 12 and 14 with the terminals of a condenser 16. The charging circuit for condenser 16 includes a source of electrical potential 18 connected to the respective terminals of the condenser through leads 19 and 20. Preferred stroboscope circuits 60 for use with the present invention are more particularly described in my aforementioned co-pending application Serial No. 709,901.

The several circuits shown in Figs. 1, 2, 3, and 75 4 are designed particularly to illustrate various

modifications of the impulse generator adapted to initiate discharge or flashing of the stroboscope tubes 10. In all of the figures the means employed includes a transformer 24 having its secondary connected by a lead 26 with an exciting electrode 22 of the tube 10. The impulse generator shown in Fig. 1 includes the primary of transformer 24 and a gaseous discharge tube 28 having its anode and cathode connected by leads in the discharge circuit of a condenser 30. 10 32 is a source of direct current energy which is connected by leads through a variable impedance VR with the terminals of condenser 30. Current may flow from 32 to the condenser at a rate controlled by VR. As soon as the potential of the condenser builds up to the breakdown voltage of the tube 28, the condenser suddenly discharges through the tube and the primary of the transformer, inducing a high voltage impulse in the secondary of the transformer 20 which is conveyed to the stroboscope 10 and initiates a flash thereof.

In the impulse generator shown in Fig. 2 the primary coil of the transformer 24 and the gaseous discharge tube 28 are connected in the 25 charging circuit of the condenser 30, and the variable impedance VR is shunted across the terminals of the condenser. Current is supplied from the energy source 32 whose potential is above the breakdown potential of tube 28. When 30 the circuit is made, current flows to charge the condenser 30 until the potential across the electrodes of tube 28 falls below the potential at which it remains conductive. Discharge of the condenser then takes place at a rate controlled 35 by VR until the breakdown potential of tube 28 is reached. The tube then suddenly becomes a conductor, and charging current suddenly flows through the tube and the transformer primary. The impulse induced at this time in the secondary 40 of the transformer is conveyed to the stroboscope lamp 10 and initiates a flash thereof.

In the impulse generator shown in Figs. 1 and 2 the gaseous conductor device has but two electrodes. It is possible to use a three electrode 45 device, a trigger tube; this is to be preferred in some cases since the breakdown potential may be varied by varying the potential of the third electrode with respect to one of the main electrodes. The gaseous discharge device may have 50 a cathode heated by appropriate means, if desired; a hot cathode tube has in general a lower potential drop while current is flowing, which may be an advantage in some cases. The variable impedance VR may have a high or low 55 ratio of inductance to resistance. Alternatively, the capacity of condenser 30 may be changed to change the rate of flashing; it is possible to change all three types of impedance in the circuit, capacitative, inductive, and resistive, or 60 any two, or only one. It is also possible to use a variable impedance in the path between the condenser 30 and the gaseous discharge device 28, but this is less desirable, since the suddenness of the current flow through the primary of the 65 transformer would be lessened.

The frequency of the impulses produced by the static inverter shown in Figs. 1 and 2 is affected by the source potential and the breakdown potential of the gaseous discharge device. I have 70 therefore developed the impulse generator shown in Fig. 3, which consists essentially of a condenser 30 which is charged from energy source 32 through an inductance L, a variable inductance impedance VR and through an electric check 75

valve V. Condenser 30 is shunted by a circuit comprising a trigger tube 34 and the primary of a spark coil transformer 24. The control electrode or grid 36 of tube 34 is connected to the 5 cathode of check valve V through the resistor R38. The secondary of spark coil 24 is connected to the exciting electrode of the stroboscope 10. The operation of the impulse generator shown in Fig. 3 is substantially as follows: 10 When the apparatus is first connected to the energy source 32 the potential of condenser 30 is zero. As soon as current starts to flow the control electrode 36 of trigger tube 34 is made negative to its cathode by the amount of drop 15 across the check valve V, which drop may be about 10 to 15 volts if V is a hot cathode mercury vapor rectifier. I prefer to employ at 34 a positive grid trigger tube, that is, one whose grid must be made positive with respect to its 20 cathode to initiate conduction with the highest anode-cathode potential to be used. However, a negative grid tube may be used, together with an auxiliary bias, if necessary. It is sufficient that the total negative bias including the drop 25 across V, be great enough to keep the tube in the non-conducting state with the highest potential to which condenser 30 will be charged. The inductance L and resistance VR are so chosen with respect to the capacitance of 30 that 30 L, VR and 30 form an oscillating circuit, preferably one which is but slightly damped. Therefore current continues to flow into condenser 30 until its potential exceeds the potential of source 32. The current is then decreasing, and eventually falls to zero. At this time the tendency is 35 for the current to reverse, and for the condenser to discharge back into the source, but this reversal is not possible because of the check valve action of V. The excess voltage is therefore 40 immediately transferred to the check valve, making its cathode positive with respect to its anode by this amount. The check valve is by-passed by the circuit comprising R-38, the control electrode 36 of tube 34, and the cathode of the trigger tube. Current therefore may flow through 45 this circuit in amount which is limited by the resistance of R38; but as soon as the control electrode 36 becomes sufficiently positive with respect to its cathode, the trigger tube 34 breaks down, 50 the condenser 30 discharges through the trigger tube and through the primary of the spark coil 24, thereby inducing a high voltage impulse in the secondary of the transformer which is conveyed to the exciting electrode of the stroboscope 10. The inductance of the spark coil 24 causes 55 the voltage of condenser 30 to become less than the cut off voltage of trigger tube 34, so that conduction ceases. The control electrode 36 then regains control and the process is repeated. The 60 discharge through the trigger tube 34 takes place exactly at the instant of maximum condenser potential, regardless of the tube characteristics, since the potential of the control electrode 36 with respect to its cathode then changes 65 constantly from negative by the amount of the drop through valve V when conducting, to positive by the amount of excess potential of the condenser over the source. The time required to reach the maximum condenser potential is independent of the source potential, so that the 70 number of impulses per second is governed only by the resistance VR, inductance of L and the capacitance of 30. The number of flashes of stroboscope lamp 10 per second may be varied by changing VR, as shown in the diagram. It

is also possible to make condenser 30 variable. Also, while it is preferred to use a stroboscope lamp 10 which is separate and distinct from the trigger tube 34, it is possible to employ the light developed by the trigger tube 34 for stroboscopic examination. An ammeter 40 in the charging circuit of condenser 30 may be calibrated in flashes per second, or alternatively the setting of the variable inductance VR or of a variable condenser used at 30, or the settings of both 10 5 may be used as a measure of the flash rate.

While the inverter shown in Fig. 3 is particularly valuable from the standpoint of constant frequency at any setting, it is in practice restricted to use for moderate and high flash rates. 15 The time between flashes is dependent on the product of inductance and capacitance used, so that for long time intervals—of the order of $\frac{1}{2}$ second or more—this product becomes inconveniently large. Also, only a comparatively narrow range of speeds can be covered with a simple variable impedance. To take care of the very low speeds, and to get a very wide range of speeds with a simple variable impedance, I have modified the circuit of Fig. 1 by using a vacuum 20 tube to limit the current flows to condenser 30, the variable impedance being used to control the current which the vacuum tube will pass. An illustration of a preferred modification of this 25 type is shown in Fig. 4.

There are two ways of controlling the current through the vacuum tube. One method employs a variable resistance in the cathode heating circuit. The electron emission is a function of the cathode temperature, so that by making the potential of the anode with respect to the cathode 30 sufficiently high, the current flow can be controlled by controlling the cathode temperature, which can be controlled by controlling the current flow to the cathode heating circuit. In practice this method is restricted to tungsten cathodes, since other commonly available cathodes may be injured by the application of anode voltage sufficient to attract all the electrons emitted. I prefer to use the second method, in which the 35 current flow is limited to a value less than the total emission by a third electrode whose potential with respect to the cathode is controlled by means of a variable resistance. In order to make the current flow to the anode substantially 40 independent of the anode potential, a fourth electrode may be employed, this fourth electrode being maintained at a constant positive potential with respect to the cathode. Even better results are obtained by employing as well a fifth 45 electrode, whose potential is also maintained constant with respect to the cathode, usually at the same potential as the cathode. My preferred method is then to use a pentode, or triple grid tube, with one grid connected to the cathode, a 50 second grid maintained at a constant potential positive with respect to the cathode, and the third grid connected to a variable resistance so that its potential with respect to the cathode can be controlled. I have found that a 58 type tube is 55 quite suitable for this purpose; flashing rates may be varied continuously from 0 to any upper limit fixed by the ionization time of the trigger tubes employed. The application of the pentode is shown in Fig. 4.

Fig. 4 is a wiring diagram of a preferred arrangement of variable frequency stroboscope tachometer. This stroboscope tachometer comprises two main circuits, one being a stroboscope and R. P. M. indicator closely resembling the ap- 75

paratus described in my aforementioned copending application Serial No. 709,901; and the other circuit comprising an impulse generator adapted for supplying excitation impulses to the stroboscope at a controlled rate.

Referring to Fig. 4, a transformer 42 is shown as energized from alternating current mains 44, the transformer serving to charge the condenser 46 through rectifier valve 47 and through inductance L⁴⁸. Condenser 46 is charged from condenser 46 through inductance L⁴⁹ and a check valve V⁵⁰. Stroboscope lamp 10 discharges condenser 16 when it is excited by an impulse impressed on its exciting electrode 22. The chief difference between the stroboscope circuit illustrated in Fig. 4 and similar circuits illustrated in my aforementioned copending application Serial No. 709,901 lies in the substitution of a ratiometer RM in place of the ammeters described in my said copending application, for use as a rate meter. The ratiometer RM is calibrated to show the ratio of the currents flowing in its two coils. One of these coils is in series circuit with the stroboscope lamp 10, and the other in parallel circuit. The current in the coil which is in parallel with stroboscope 10 is proportional to the supply voltage, so that the instrument readings are independent of supply voltage variations.

The impulse generating apparatus for exciting the stroboscope lamp 10, as it is illustrated in Fig. 4, comprises a transformer 51 which is energized from A. C. mains 52 and which transformer supplies induced current which is rectified by a valve 53 and filtered by inductance L⁵⁴ and a condenser 55 to a voltage divider comprising a resistor R⁵⁶, glow tubes T⁵⁷ and T⁵⁸, and a potentiometer R⁵⁹. The glow tubes T⁵⁷ and T⁵⁸ serve to maintain constant the potential between their electrodes. The constant potential between the electrodes of glow tube T⁵⁸ is impressed between the cathode and screen grid of pentode tube P⁶⁰, while any desired fraction of the constant potential between the electrodes of glow tube T⁵⁷ is impressed between the cathode and the control grid of pentode P⁶⁰.

Another voltage divider which consists of resistor R⁶¹, potentiometer R⁶² and glow tube T⁶³, is supplied with direct current from any convenient source such as the source from which the condenser 46 of the stroboscope circuit is charged. From the potential across R⁶¹ condenser 30 is charged through pentode P⁶⁰ at a rate which is controlled by the potential between the cathode and control grid of pentode P⁶⁰, and which rate is independent of the potential across R⁶¹ so long as the potential across 30 is substantially less than the potential across R⁶¹. The potential across condenser 30 is impressed between the anode and cathode of trigger tube 64, while any desired fraction of the constant potential between the electrodes of glow tube T⁶³ is impressed between the grid 36 and cathode of trigger tube 64. For each value of grid-cathode potential in trigger tube 64 there exists a maximum value of anode-cathode potential. As soon as this maximum anode-cathode potential is reached, the trigger tube breaks down and current flows. Thus condenser 30 is charged to the maximum potential corresponding to the position of potentiometer R⁶² and then discharges through the primary of transformer 24, thereby inducing in the secondary of transformer 24 a high voltage impulse which excites stroboscope lamp 10 to discharge condenser 16.

It is possible to control the interval between flashes of stroboscope 10 by adjusting potentiometer R⁵⁹ or by adjusting R⁶², but I prefer to use R⁵⁹ to control the flash rate, and to use R⁶² only to adjust from time to time to compensate for any changes in characteristics in trigger tube 64.

While the apparatus for controlling impulse rates hereinbefore described is the preferred means for accomplishing the objects of the present invention, other possible means of control may be used including circuits adapted to change the capacity of condenser 30, and circuits adapted to change the screen grid potential of pentode 60.

Having thus described my invention, what is claimed as new is:

1. In combination with apparatus for producing electrical energy flashes of the type in which a condenser is periodically discharged through a gaseous conductor lamp, means for initiating discharge of the condenser at selected intervals consisting of a static inverter for producing electrical impulses at a controlled rate, said inverter comprising a gaseous discharge device connected in circuit with a source of potential and with means for varying the impulse rate comprising a variable impedance, and means for conveying such impulses to the flash producing apparatus.

2. In combination with apparatus adapted for excitation by electrical impulses, means for exciting such apparatus comprising a condenser, a source of energy for charging the condenser, means connected in series circuit with the energy source and with the condenser for charging the condenser to a potential higher than the potential of the energy source, said means comprising an electric check valve and an inductance forming with the condenser a slightly damped oscillating circuit, means for discharging the condenser at selected intervals, and means for conveying the voltage impulse which occurs at the instant that current ceases to flow through said electric check valve.

3. Apparatus of the type defined in claim 1 in which the gaseous discharge device is a gaseous conductor device having at least three electrodes of a type in which the maximum potential which can be established between two main electrodes without appreciable current flow therebetween may be controlled by controlling the potential between one of said main electrodes and a third electrode.

4. Apparatus of the type defined in claim 1 in which the static inverter includes a second condenser arranged in series circuit with the gaseous discharge device and the source of potential.

5. Apparatus of the type defined in claim 1 in which the static inverter includes a second condenser shunted across the gaseous discharge device.

6. In combination with apparatus for producing electrical energy flashes of the type in which a condenser is periodically discharged through a gaseous conductor lamp, means for initiating discharge of the condenser at selected intervals consisting of a static inverter for producing electrical impulses at a controlled rate, said inverter comprising a gaseous discharge device in series circuit with a source of potential and with a second condenser, and means for varying the impulse rate comprising a variable impedance shunted across said second condenser, and means for conveying such impulses to the flash producing apparatus.

7. In combination with apparatus for produc-

- ing electrical energy flashes of the type in which a condenser is periodically discharged through a gaseous conductor lamp, means for initiating discharge of the condenser at selected intervals consisting of a static inverter for producing electrical impulses at a controlled rate, said inverter comprising a gaseous discharge device connected in circuit with a source of potential, a second condenser shunted across the gaseous discharge device, and means for varying the impulse rate comprising a variable impedance connected in the charging circuit of the second condenser, and means for conveying such impulses to the flash producing apparatus.
15. 8. In combination with apparatus for producing electrical energy flashes of the type in which a condenser is periodically discharged through a gaseous conductor lamp, means for initiating discharge of the condenser at selected intervals consisting of a static inverter for producing electrical impulses at a controlled rate, said inverter comprising a gaseous discharge device connecting in circuit with a source of potential, a second condenser shunted across the gaseous discharge device, and means for varying the impulse rate comprising a vacuum tube connected in the charging circuit of the second condenser together with means for controlling the current flowing through said vacuum tube, said means comprising a variable impedance.
30. 9. In combination with apparatus for producing electrical energy flashes of the type in which a condenser is periodically discharged through a gaseous conductor lamp, means for initiating discharge of the condenser at selected intervals consisting of a static inverter for producing electrical impulses at a controlled rate, said inverter comprising a gaseous discharge device connected in circuit with a source of potential, a second condenser shunted across the gaseous discharge device, and means for varying the impulse rate comprising a vacuum tube connected in the charging circuit of the second condenser, said vacuum tube having at least three electrodes and being of the type in which current flowing between the anode and the cathode may be controlled by varying the potential between the cathode and the third electrode, together with means for varying the potential between the cathode and said third electrode.
45. 10. Apparatus of the type defined in claim 9 in which said vacuum tube is of the type having at least four electrodes in which current flowing between the anode and the cathode may be controlled by varying the potential between the cathode and the third electrode, together with means for maintaining a substantially constant potential between the cathode and the fourth electrode.
50. 11. Apparatus of the type defined in claim 9 in which said vacuum tube has at least five electrodes and is of the type in which the current flowing between the anode and the cathode may be controlled by varying the potential between the cathode and a third electrode, together with means for maintaining a substantially constant potential between the cathode and the fourth electrode, and means for maintaining a substantially constant potential between the cathode and the fifth electrode.
55. 12. Apparatus of the type defined in claim 9 in which the gaseous discharge device is a gaseous conductor device having at least three electrodes of the type in which the maximum potential which can be established between two main electrodes without appreciable current flow there-
- between may be controlled by controlling the potential between one of said main electrodes and a third electrode; and in which said vacuum tube has at least five electrodes and is of the type in which current flowing between the anode and the cathode may be controlled by varying the potential between the cathode and a third electrode, together with means for maintaining a substantially constant potential between the cathode and a fourth electrode, means for maintaining a substantially constant potential between the cathode and a fifth electrode, and means for controlling the potential between one of the main electrodes and a third electrode of said gaseous discharge device.
15. 13. A static inverter comprising a condenser, a source of potential for charging the condenser, means connected in series circuit with the energy source and with the condenser for charging the condenser to a potential higher than the potential of the energy source, said means comprising an electric check valve and an inductance forming with the condenser an oscillating circuit, means for discharging the condenser comprising a gaseous discharge device having at least three electrodes and of the type in which the maximum potential which can be established between two main electrodes without appreciable current flow therebetween may be controlled by controlling the potential between one of said main electrodes and a third electrode; said condenser discharge means also including means for impressing between the third electrode and one of the main electrodes of said gaseous conductor device the voltage impulse which occurs at the instant current ceases to flow through said electric check valve.
30. 14. A static inverter of the type defined in claim 13, embodying as an additional element a variable impedance for controlling the intervals between condenser discharges.
35. 15. A static inverter of the type defined in claim 13 in which the cathode of the gaseous discharge device is connected to the anode of the electric check valve and to one side of the condenser, in which the anode of the gaseous discharge device is connected to the other side of the condenser, and in which a third electrode of the gaseous discharge device is connected to the cathode of the electric check valve.
50. 16. A static inverter of the type defined in claim 13 embodying as an additional element a variable impedance for controlling the intervals between condenser discharges, and also embodying an ammeter in the condenser charging circuit whereby the number of condenser discharges per unit of time is measured.
55. 17. In combination with apparatus for producing electrical energy flashes of the type in which a condenser is periodically discharged through a gaseous conductor lamp, means for initiating discharge of the condenser at selected intervals consisting of a static inverter for producing electrical impulses at a controlled rate, said inverter comprising a second condenser, a source of energy for charging the condenser, means connected in series circuit with the energy source and with the second condenser for charging the second condenser to a potential higher than the potential of the energy source, said means comprising an electric check valve and an inductance forming with the second condenser a slightly damped oscillating circuit, means for discharging the second condenser comprising a gaseous discharge device having at least three electrodes.

of the type in which the maximum potential which can be established between two main electrodes without appreciable current flow therebetween may be controlled by controlling the potential between one of said main electrodes and a third electrode, means for impressing between said third electrode and one of the main electrodes of said gaseous discharge device the voltage impulse which occurs at the instant current ceases to flow through said electric check valve, together with means for varying the impulse rate comprising a variable impedance included as an element in the inverter circuit, and means for conveying such impulses to the flash-producing apparatus.

18. Electric flash producing apparatus for measuring rates comprising a condenser, a source of energy for charging the condenser, means connected in series circuit with the energy source and with the condenser for charging the condenser to a predetermined potential higher than the potential of the energy source, said means comprising an electric check valve and an inductance forming with the condenser a slightly damped oscillating circuit, means for discharging

the condenser periodically, the number of discharges per unit of time being proportional to the rate to be measured, and a ratiometer having one coil connected in series circuit with the condenser and having another coil connected in parallel circuit with the condenser. 5

19. A variable frequency stroboscope comprising a condenser, means for charging said condenser, a gaseous conductor lamp shunted across said condenser, and means for initiating discharge of said condenser through said gaseous conductor lamp at selected intervals comprising a relaxation inverter and a transformer, said relaxation inverter comprising a second condenser, a source of energy for charging said second condenser, a gaseous discharge device adapted to discharge said second condenser when its potential reaches a selected value lower than that of the energy source, and means for controlling the time required for said second condenser to be charged to said selected value comprising a five electrode vacuum tube and means for controlling the current flowing through said five electrode vacuum tube. 10 15

BENJAMIN MILLER. 25

CERTIFICATE OF CORRECTION.

Patent No. 2,043,484.

June 9, 1936.

BENJAMIN MILLER.

It is hereby certified that error appears in the printed specification of the above numbered patent requiring correction as follows: Page 2, second column, line 74, strike out the word "inductance"; page 3, second column, line 9, for "inductance" read impedance; and that the said Letters Patent should be read with these corrections therein that the same may conform to the record of the case in the Patent Office.

Signed and sealed this 8th day of September, A. D. 1936.

Leslie Frazer

(Seal)

Acting Commissioner of Patents.
